UNITED STATES PATENT OFFICE

WALTER W. WILLIAMS, OF BLOOMINGTON, ILLINOIS, ASSIGNOR TO WILLIAMS OIL-O-MATIC HEATING CORPORATION, OF BLOOMINGTON, ILLINOIS, A CORPORATION OF ILLINOIS

FUEL AND AIR CONTROL

Original application filed June 18, 1928, Serial No. 286,314. Divided and this application filed January 17, 1930. Serial No. 421,375.

This invention relates to improvements in liquid fuel burning devices for domestic purposes and more particularly to fuel and air controls for the operation thereof and is a division of my prior co-pending application, Serial No. 286,314, filed June 18, 1928.

Certain types of domestic liquid fuel heaters supply the liquid fuel by gravity to a pot or combustion chamber adapted to be inserted within the fire box of the furnace or heater of a house heating system and in which air for combustion is supplied to the combustion chamber from a casing surrounding the side and bottom of the combustion chamber and having an air intake leading therefrom, the air for combustion entering through apertures arranged in the walls of the combustion chamber and the amount of air passing therethrough regulated by a damper in the air intake. In burners of this type the flame is either initially ignited by the throwing into the combustion chamber of a piece of burning paper or match or by a gas pilot and the combustion occurs as the incoming fuel spreads over the base of the combustion chamber and vaporizes and mixes with the air coming in through the sides of the combustion chamber. The height above the bottom of the combustion chamber at which said vapors burn varies with the amount of oil and air supplied so that when a small amount of oil is supplied, and a small amount of air is provided the flame occurs near the bottom of the chamber and upon increasing the supplies of both oil and air in proper proportions, the vapors burn at or about the top of the combustion chamber.

It is an object of this invention to provide a device of this character which will automatically burn with a low flame when first ignited and provide an electric thermostatic control to be placed in a room of the dwelling where the temperature is desired to be maintained at a certain degree which control, when the temperature falls below the desired degree, will not only operate a valve to increase the amount of oil supplied to the burner and provide a thermostatic control actuated by the temperature of the bottom of the combustion chamber to increase the supply of air

automatically as the oil supply is increased and which will act conversely when the temperature of the room exceeds that of the desired amount whereby both the oil and air supply will be reduced to the minimum under which the flame will continue to burn.

In explaining the embodiments of this invention reference is made to the accompanying sheets of drawings illustrating the preferred forms, it being understood that the invention is not restricted to the particular burner shown nor to the particular type of float valve oil supply and that minor detail changes may be made in the various controls without departing from the scope of the invention.

In the drawings:

Figure 1 is a view in side elevation of one embodiment of this invention with parts of the combustion chamber broken away and with the wiring to the electric controls shown in diagram.

Figure 2 is a fragmentary top plan view of Figure 1 with parts broken away and with the motor omitted.

Figure 3 is a transverse sectional view of the float valve oil supply device.

Figure 4 is a fragmentary view in side elevation with parts broken away of another embodiment of this invention showing the application of the thermostatic or bi-metallic control upon the underside of the combustion chamber and the damper operating mechanism actuated thereby arranged on the side of the draft pipe.

Figure 5 is a top plan view of the thermostatic or bi-metallic control, as shown in Figure 4.

Figure 6 is a modified form of the damper control apparatus as actuated by a thermostatic or bi-metallic control secured to the underside of the combustion chamber.

Figure 7 is a fragmentary view partly in side elevation illustrating a modified bi-metallic damper operating mechanism.

As a means of describing the improved controls forming the subject-matter of this invention, a domestic liquid fuel burning mechanism for domestic heating purposes is illustrated with the understanding that the

invention is not restricted to the particular application thereof, as shown. The liquid fuel burner comprises a cylindrical combustion chamber 1 provided with a plurality of air inlets 1* in the sides and provided with a closed bottom 2 and open at the top. A cylindrical casing 3 surrounds the sides and bottom of the combustion chamber and is provided with an air intake in the form of a rectangular draft pipe 4 extending from one side thereof adjacent the bottom and opening at the other end into a fan blower housing 5. The cylindrical casing 3 joins the top of the side walls of the combustion chamber 1 which side walls are provided with a plurality of small openings arranged in tiers parallel to the bottom of the chamber. A fan blower 6 is mounted within the fan housing 5 and is preferably operated by the motor shaft of a small motor 7 supported thereabove. A float operated oil valve chamber 8 is preferably mounted on the draft pipe 4 adjacent the motor 7 which is connected by the pipe 9 to an oil tank or other source of liquid fuel, not shown, through which the liquid fuel is supplied to the float chamber. The underside of the float chamber is connected to a fuel discharge pipe 10 which extends centrally of the draft pipe 4 to the center of the lower side of the bottom 2 of the combustion chamber 1 and at which point is provided with a discharge opening into the combustion chamber. The float valve chamber 8 is a commercial article and form no part of this invention, it being sufficient for the understanding of the operation of the device to state that this chamber is provided with two discharge valves 11 and 12. The valve 11 is manually set to supply sufficient oil to the combustion chamber to allow combustion to occur therein with the flame adjacent the bottom of said chamber and the valve 12, while normally remaining closed, may be manually or otherwise lifted to admit sufficient oil to pass into the oil pipe 10 to provide additional fuel to the combustion chamber, which, when sufficient air is mixed with the vapors thereof as to cause the flame to burn in a plane adjacent the top of the combustion chamber.

The electricity employed to operate the motor 7 is taken from the commercial line and passes through the house switch S by way of wire 13 to the motor and back through wire 14 to the house switch. A transformer 15 is shown mounted upon the motor which is connected in parallel with the commercial circuit 13 and 14. The secondary circuit passes from one terminal of the transformer 15 through wire 16 to the boiler control B and from the boiler control by the way of wire 17 to a room thermostat T and thence by way of wire 18 to an electric heating coil 19 arranged about a strip of bi-metallic metal 20 secured at one end to the top of the float

valve chamber 8 and having the other free end in engagement with the high fire valve 12 and so arranged that when the bi-metallic strip is heated by the heating element 19 it will raise the valve 12 and admit additional oil to the combustion chamber. From the heating coil 19 the secondary circuit passes through wire 21 back to the other terminal of the transformer 15. The boiler control is a commercial article and varies in type with the type of heating system to which the burner is applied. If the heating system is a hot water system the boiler control stem enters into the water within the boiler and is responsive to the temperature thereof. If a steam system, the stem of the boiler control enters the boiler above the water line and is responsive to the steam pressure therein, and if hot air or vapor system, the control is responsive to the temperature thereof. The control as shown includes a mercury tube switch which is normally in closed position and when the conditions within the boiler approach the danger line the control responds thereto and operates the mercury tube switch to break the circuit therethrough. The room thermostat is also a commercial article and forms no part of this invention. As illustrated, the room thermostat comprises a mercury tube switch and includes mechanism responsive to the temperature of the room in which the thermostat is located to close the circuit when the temperature descends to a certain degree and to break the circuit when the temperature rises to a certain degree.

In this type of burner mechanism it is seen that the fan-blower is continuously operating as long as the house switch S remains closed and the amount of air supplied through the draft pipe 4, circular casing 3 and through the holes in the side walls of the combustion chamber 1 is sufficient to maintain a high fire condition provided sufficient liquid fuel is supplied to the combustion chamber. It is therefore necessary when the amount of oil supplied to the combustion chamber is decreased to correspondingly decrease the air supply. To accomplish this a damper 22 is mounted within the draft pipe 4 of such a size that when in closed position only sufficient air will pass thereby from the fan blower to the combustion chamber to mix the fuel vapors to provide a low fire where the flame occurs adjacent the bottom of the combustion chamber. This damper 22 is provided with a pivotal member which extends beyond the side of the draft pipe 4 and is bent adjacent its end to form an operating lever 23 whereby the damper may be rotated from open to closed position. A U-shaped strip of bi-metallic metal 24 is secured to the underside of the combustion chamber, as shown in Figure 2, in which one arm is securely held against the end of a pipe 25 also secured to the underside

of the bottom of the combustion chamber which pipe passes out through the side of the cylindrical casing 3 and extends parallel to the draft pipe for a short distance. The 5 free end of the bi-metallic strip 24 is attached to a rod 26 which passes through the pipe 25 and is adapted to engage a pivoted lever 27, preferably mounted in a bracket carried upon the extremity of the pipe 25. The 10 free end of this lever is connected to the free end of the lever 23 of the damper by a rod 28 so that upon movement of the free arm of the strip of bi-metallic metal 24, the damper will be swung about its pivot. In Figure 1, upon 15 closing the house switch S, the motor will begin to operate and the burner may be ignited and will burn with a low fire which will produce sufficient heat upon the bottom of the combustion chamber 2 to cause the thermostatic member 24 to expand and thereby through rod 26, lever 27, and rod 28, will cause the damper 22 to assume the position shown, and the burner will operate indefinitely this 20 way as long as fuel is supplied to it. The boiler control B is shown closed while the room thermostat T is shown in the open position. When the temperature of the room in which the thermostat is located drops below the desired degree, the thermostat will close 25 the secondary circuit from the transformer whereupon the heat coil 19 will cause the strip of bi-metal 20 to move upward and open the high fire valve 12 whereupon additional oil will flood the bottom of the combustion chamber reducing the temperature thereof and causing the thermostatic member 24 to cool and contract, whereby the damper 22 will be 30 opened which will supply sufficient air to the combustion chamber to cause the flame to burn adjacent the top of the chamber whereby the bottom of the combustion chamber will remain sufficiently cool to cause the U-shaped strip of bi-metallic metal 24 to remain contracted. The burner will then continue to 35 burn with a high fire until the room thermostat breaks the secondary circuit whereupon the heating element 19 will cool and the bi-metallic strip of metal 20 will close the high fire valve, cutting down the supply of oil to 40 the combustion chamber, and as the flame descends toward the bottom, the heat thereof will expand the U-shaped strip 24 and cause the damper to close and the burner will burn with the low fire as long as oil is supplied to it 45 until the room thermostat again calls for heat.

Figures 4 and 5 illustrate a modified type of combustion chamber controlled thermostatic mechanism. In this case a strip of bi-metallic metal 29 secured at its center to a 50 block mounted in a housing 30, which housing is secured to the underside of the bottom of the combustion chamber 2, is shown. The free ends of the strip of bi-metallic metal are then curled about themselves and toward 55 each other, as shown in Figure 5, and their

free ends engaged in a loop in the rod 26 whereby this particular type of thermostatic control operates the rod 26 in the same manner as the U-shaped strip of bi-metallic metal 24. As illustrated in Figure 4, the 70 rod 24 engages a lever 31 which is mounted on the end of a central pivoted member of the damper 22 and normally, by means of springs 32, holds the damper in open position when the coils of the thermostatic metal 29 are 75 coiled.

Figure 6 illustrates another form of damper control mechanism. In this case a straight strip of bi-metallic metal 33 is secured at one side of the fuel inlet to the combustion chamber at one end by bracket 33^a mounted upon the underside of the bottom 2 of the combustion chamber 1 which also supports the pipe 25. The strip 33 normally departs from the bottom 2 from its fixed end until the free 80 end is at a distance therefrom. The free end is connected by a link 34 to a bell crank lever 35 pivotally supported in a bracket 36 extending from the underside of the bottom 2 of the combustion chamber with the other arm 85 connected to the rod 26 whereby, when the fuel is ignited and burns in the combustion chamber adjacent the bottom, the heat thereof will cause the thermostatic strip to curl upward until its movement is limited by contact to the bottom 2. This movement will be transmitted through the rod 26 to close the damper as hereinbefore described. 90

Figure 7 illustrates a modified form of damper operating mechanism which also includes a motor switch. When this type of mechanism is employed the motor only operates when the fuel is burning with a high fire within the combustion chamber. This mechanism is shown as including a casing 37 mounted upon the side of the draft pipe 4 adjacent the damper 22 and is engaged by the end of the tube 25 through which the rod 26 passes from the underside of the combustion chamber. Any desired type of combustion chamber responsive thermostat can be employed to operate the rod 26. The free end of the rod 26 is shown in engagement with a lever 38 mounted at its upper end upon the casing 37 and with its lower end connected by a rod 39 to the operating lever 23 of the damper 22. The lever 38 mounts the mercury tube switch 40 in the manner shown, which mercury tube switch is in the motor circuit. 105

When the burner is burning with a low fire the combustion chamber responsive thermostatic mechanism will cause the rod 26 to move in the direction of the combustion chamber tilting the lever 38 about its pivot so that the circuit will be broken through the mercury tube switch to the motor and at the same time the damper 32 will be closed, whereby it is seen that the motor remains idle while the burner is burning with a low fire. When the room thermostat calls for 110

heat an additional oil is supplied to the combustion chamber and the bottom of the chamber will be flooded cooling the chamber sufficiently to allow the thermostatic member to contract whereby the rod 26 causes the lever 38 to tilt in the position shown in Figure 7. This closes the motor circuit through the mercury tube 40 and at the same time opens the damper 22 whereby the additional air required for the high fire will be immediately supplied through the operation of the motor and the motor will continue to operate as long as the room thermostat calls for heat. When the room thermostat breaks the secondary circuit, the supply of oil is reduced and the fire in the burner assumes the lower position increasing the temperature of the bottom of the combustion chamber, the thermostatic member 29 will expand and cause the rod 26 to move to the right whereby the lever 38 will be tilted and cause the mercury tube switch to break the motor circuit at the same time closing the damper 22. This arrangement is more economical than the ones heretofore described inasmuch as the motor is only operating when a high fire is desired.

What I claim is:

A domestic liquid fuel heating device comprising in combination, a burner including a liquid fuel receptacle, an air supply means therefor including a conduit, a fuel supply means including two controls therefor, one of which controls permits fuel to flow to said receptacle at a minimum rate, a room thermostat adapted to actuate the other of said controls to permit fuel to flow to said receptacle at a maximum rate, a thermostat adjacent the receptacle and operative in accordance with a minimum supply of fuel to decrease the air supply, and operative in accordance with a maximum supply of fuel to increase the air supply.
